ROTARY MACHINE BUSHING ARRANGE-
MENTRural Welton Whann, Los Angeles, Calif., assign-
or to Emsco Derrick & Equipment Company,
Los Angeles, Calif., a corporation of California

Application August 9, 1939, Serial No. 289,225

7 Claims. (Cl. 255—23)

My invention relates to improvements in table and bushing assemblies of the general type which are employed on rotary machines in the drilling of oil wells.

5 It is the general object of my invention to provide the rotary machine with a table, a table bushing, and a drive bushing, in which the table bushing and drive bushings are separately driven by and supported within the table opening in order that driving forces or weight of the drive bushing will not be transmitted to the table bushing. This general subject is similar to that of the copending applications of Black and Brewster, Serial No. 197,400, Rotary machine; Davidson, Serial No. 228,585, Rotary machine and bushing therefor; and Davidson, Serial No. 233,967, Rotary machine, which applications are owned by applicant's assignee.

20 My invention relates to a specific improvement over the prior art and consists essentially in a combination in which the table opening has but a single supporting shoulder which lies in a single horizontal plane and in which the table and drive bushings are so formed that when they are assembled the supporting shoulders on these two bushings also rest in the same plane. This arrangement leads to simplicity and enables a very compact bushing arrangement with the upper surface of the bushing or bushings flush with the top surface of the table.

25 It is accordingly an object of my invention to provide a rotary machine having a rotary table and bushing assembly in which the table has but a single shouldered section at the upper end of the table opening and in which both the table bushing and the drive bushing are each separately supported by a single supporting shoulder in the shouldered section, the supporting shoulders of the bushings being located in the same horizontal plane when the parts are thus assembled.

30 Other objects and advantages of my invention will be pointed out in the course of the following detailed description of alternative forms of my invention. It should be understood that various modifications and alterations may be made in the structure of my invention without departing from the spirit and scope thereof as defined in the appended claims.

35 Referring to the drawings in detail:

40 Fig. 1 is an elevational view partly in section showing a preferred form of my invention, this view being taken as indicated by the line 1—1 of Fig. 3.

45 Fig. 2 is a fragmentary sectional view taken as indicated by the line 2—2 of Fig. 3.

50 Fig. 3 is a horizontal fragmentary sectional view taken as indicated by the line 3—3 of Fig. 1.

55 Fig. 4 is a perspective view of the rotary table, drive bushing, and the table bushing in separated relationship so that the shape of the parts and arrangement of the shoulders may be clearly illustrated.

60 Fig. 5 is a fragmentary elevational view showing the drive bushing removed and the slips in position in the table bushing and supporting the drill pipe.

65 Fig. 6 is a fragmentary sectional view showing an alternative form shoulder arrangement of the drive and table bushings, this section being taken through the shouldered portion of the drive bushing.

70 Fig. 7 is a similar fragmentary sectional view of the alternative form of my invention, this view being taken through the shouldered section of the table bushing.

75 Referring to Figs. 1 to 5, inclusive, the numeral 11 represents a base on which a rotary table 12 is rotatably supported by a main bearing 14. The table 12 supports a ring gear 15 which is engaged by a pinion 16, which pinion is supported on a shaft 17 which may be rotated through the medium of a sprocket 18. The general construction of the rotary machine does not constitute the essence of the present invention and my invention which may be incorporated in any of the various designs of rotary machines now in common use in the industry will be described.

80 The table 12 has a table opening 24 which is concentric to the axis of rotation and has a shouldered section 27 and a skirt section 28. The shouldered section is preferably of polygonal cross-section and has vertical walls 29 which constitutes a driving shoulder and has a lateral or horizontal wall 30 which constitutes a supporting shoulder. The supporting shoulder 30, in my invention, is located in a single horizontal plane. It will be noted that the vertical walls 29 are positioned at angles to each other so that in plan 85 there are a series of circularly arranged pockets 31 which surround the upper end of the skirt portion 28 and which constitute the upper end of the table opening 24. It should be further noted that each pocket 31 is formed by a pair of vertical walls or driving shoulder means 29 and a part or portion of the supporting wall or supporting shoulder 30. The number of pockets 31 which are provided may be varied, but it is preferable to have eight pockets in order to provide at least 90 50 55 60 65 70 75 80 85 90 95 100 105 110 115 120 125 130 135 140 9715 9720

four areas of support for each of the bushings, as will be described in the course of the following detailed description. It is also preferable that these pockets be equally spaced in circular arrangement and that they be of the same size and shape in order that the bushings need not be placed in any certain manner other than is necessary for one bushing nesting with relation to the other.

10 In Fig. 5 I have illustrated a table bushing 37 positioned in place within the table opening 24. This table bushing is preferably split into two halves 38, as shown in Fig. 4, so that it may be installed in the table opening while a drill pipe, 15 such as 40, is extending through one table opening. The table bushing 37 has an upper shouldered portion 41 and a lower cylindrical portion 42. The shouldered portion 41 rests in the shouldered section 27 and has an upright driving shoulder 43 which engages the driving shoulder 29 in certain of the pockets 31 whereby relative rotation of the table and bushing is prevented and whereby the table may be caused to drive the table bushing. The shouldered portion 41 also 20 has a lateral supporting shoulder 44 which may be considered as being formed of a plurality of supporting shoulder portions. The supporting shoulder 44 is adapted to engage the supporting shoulder 30 in certain of the pockets 31, as will 25 be described. It will be noted that the shouldered portion 41 is substantially rectangular in a cross-section and that it includes corners or projections 45 which are adapted to extend into alternate pockets 31. Each of the corners therefore provides 30 a supporting shoulder portion and a driving shoulder portion which engage a supporting shoulder portion 30 and a driving wall portion 29 in certain of the pockets 31.

The cylindrical portion 42 of the table bushing 37 has a cylindrical wall 46 which may engage the wall of the skirt section 28. The table bushing has an inner wall 47 which is conical or tapered, as illustrated, and receives a plurality of pipe supporting slips 48 which, as illustrated in Fig. 5, engage and support the drill pipe 40. There are preferably three slips which are inserted into the table opening from the top thereof by workmen on the derrick floor, and which slips may be provided with suitable handles, not shown.

50 This table bushing 37 is concentrically supported in the table opening and supports the slips 48 in a concentric and aligned position in order that the drill pipe 40 will be properly engaged and supported. It is found in practice that 55 when the parts are not thus supported there is considerable injury done to the drill pipe 40 which weakens and makes it unsafe for operation and requires replacement.

In Figs. 1 to 3, inclusive, I have illustrated my invention with a drive bushing 50 in place and with the parts in the position they occupy when a drive kelly 49 is being driven. This drive bushing or kelly bushing, as it is sometimes referred to, is preferably formed in two parts 51, as illustrated in Fig. 4, and has a central opening 54 which is preferably of rectangular cross-section or other polygonal cross-section corresponding to the cross-sectional shape of the kelly 49.

This drive bushing 50 has a shouldered portion 56 which has vertical walls 59 arranged at angles to each other and which constitute a driving shoulder which may be considered as dividing into driving shouldered portions, this driving shoulder 59 being adapted to engage the driving shoulder 29 in certain of the pockets 31. It will be noted

that the shouldered portion 56 has the shape of an eight-pointed star, thus providing a series of corners or projections 60 which extend into each of the pockets 31. Therefore, there is driving engagement of each projection with the driving 5 walls of each pocket 31.

Alternate projections 60 are provided with depending portions 61, the lower ends of which provide a supporting shoulder 62, this supporting shoulder 62 being divided into portions, there being a portion formed on each of the depending portions 61. The drive bushing is positioned in the table opening so that the projections including the depending portions 61 and the supporting shoulder portion 62 rest in the pockets 31 which 15 are unoccupied by the projections 45 of the table bushing 37. This is illustrated in the horizontal sectional view, Fig. 3.

The supporting shoulder 62 engages the portions of the supporting shoulder 30 which are 20 within the pockets 31 occupied by the depending portions 61. The depending portions 61 are of such a size that there is a small space 63 provided between the drive bushing and table bushing in order that there will be no contact of these parts. 25 The projections 60 which do not have the depending portions 61 are provided for two reasons, first, to give additional driving shoulder area, and, second, to fill the upper ends of the pockets in which the projections 45 rest in order that the upper 30 surface of the table and bushing arrangement will be substantially smooth.

The drive bushing 50 has a depending portion 65 of conical exterior which extends into the table bushing 37. This portion 65 is provided so 35 that the driving shoulders of the opening 54 may be sufficiently long to properly distribute the driving force to the kelly 49. It will be noted that this space 63 between the drive bushing and the table bushing exists between the portion 65 and 40 the table bushing so that there is no contact whatsoever between these parts.

From the foregoing it will be seen that there is no weight transmitting contact between the drive and table bushings, since these parts are 45 preferably separated by the small space 63. The table therefore independently supports the drive bushing and the table bushing, and the table also independently drives the drive bushing and the table bushing. This supporting and driving of 50 the bushing is accomplished by drive shoulders formed wholly within the table opening and by a single supporting shoulder located in a horizontal plane which is also located within the table opening. The table bushing may remain in place at 55 all times ready for use, but is used only when the slips 48 are in use. The table bushing of my invention is not called upon to support or drive the drive bushing and therefore the walls or shoulders thereof are not subjected to wear which would 60 result if the table bushing supported and drove the drive bushing. It will be seen therefore that the interengaging shoulders and surfaces between the table and table bushing will remain in good condition and alignment over a long period of time and will support the slips 48 in a concentric and aligned position over long periods of use.

In Figs. 6 and 7 I have illustrated an alternative form of my invention which enables both of the shouldered sections of the two bushings to 70 be made of equal height. As shown in Fig. 6, the table bushing 37a, which resembles the table bushing 37 except for the differences which will be pointed out, is provided with a slot 80 through which the corner or projection 60a of the drive 75

bushing 50a extends. It will be noted that this projection 60a is of the full height of the pocket 31a and need not be provided with depending portions as in the first form of my invention. As shown in Fig. 7, the table bushing 31a is provided with a shouldered portion having corners or projections 45a which also are of the same height as the pockets 31a. To accommodate these projections 45a the drive bushing 50a is provided with 10 slots 81.

This arrangement of my invention enables both bushings to be supported on the same horizontal supporting shoulder of the rotary table and enables a nesting of one bushing within the other, 15 thus enabling both bushings to be flush with the top of the table and giving ample space to incorporate means, not shown, for locking the bushings in the rotary table.

In the foregoing I have illustrated the two 20 forms in which my invention may be embodied. As stated heretofore, the principle of my invention resides in the supporting of both bushings on a supporting shoulder located in a single horizontal plane. I desire my invention to be construed in accordance with the spirit and scope 25 of the appended claims.

I claim as my invention:

1. In a rotary machine of the class described, the combination of: a base; a rotary table supported by said base, said table having a table opening which includes a plurality of supporting shoulder portions and a driving shoulder; a table bushing in said opening having a driving shoulder engageable with said driving shoulder of said table 30 opening, and having a supporting shoulder engageable with a part of said supporting shoulder portions; and a drive bushing in said table opening having a driving shoulder engageable with said driving shoulder of said table opening, and 35 having a supporting shoulder engageable with a part of said supporting shoulder portions, said supporting shoulders of said bushings being in the same horizontal plane.

2. In a rotary machine of the class described, the combination of: a base; a rotary table supported by said base, said table having a table opening in which there is a plurality of circularly arranged pockets, each pocket having supporting and driving walls, the supporting walls being in 40 the same horizontal plane; a table bushing in said opening having a shouldered portion which in-

cludes driving and supporting shoulders and which rests in at least one of said pockets and being engageable with the shoulders thereof; and a drive bushing in said opening having a shouldered portion which includes driving and supporting shoulders and which rests in at least one of said pockets and being engageable with the shoulders thereof, said supporting shoulders of said bushings being in the same horizontal plane. 5

3. In a rotary machine of the class described, 10 the combination of: a base; a table rotatably supported by said base, said table having a table opening with circularly arranged pockets having supporting shoulders located in the same horizontal plane; a table bushing in said table opening having a shouldered portion resting in certain of said pockets; and a drive bushing in said table opening having a shouldered portion resting in other of said pockets, said shouldered portions of said bushings having supporting shoulders located 15 in the same horizontal plane.

4. A combination as defined in claim 3 in which said shouldered portion of said drive bushing extends above said table bushing and has depending means on which said supporting shoulder thereof 20 is formed.

5. A combination as defined in claim 3 in which said table bushing has slot means through which extends at least a part of said shouldered portion of said drive bushing. 30

6. A combination as defined in claim 3 in which both of said bushings are substantially flush with the top of said table and in which said table bushing has slot means through which extends at least a part of said shouldered portion of said 35 drive bushing.

7. In a rotary machine of the class described, the combination of: a base; a table rotatably supported by said base, said table having a table opening with a series of circularly arranged pockets having supporting shoulders located in the same horizontal plane; a table bushing in said table opening having a shouldered portion having projections resting in alternate of said pockets; and a drive bushing in said table opening having a shouldered portion having projections resting in other of said pockets, said projections of said bushings having supporting shoulders located in the same horizontal plane. 40

R. WELTON WHANN.
